(57) **CLAIM**

The ornamental design for electronic game machine, as shown.

DESCRIPTION

FIG. 1 is a perspective view of the electronic game machine according to the present invention.

FIG. 2 is a right side view of the electronic game machine of FIG. 1.

FIG. 3 is a left side view of the electronic game machine of FIG. 1.

FIG. 4 is a front view of the electronic game machine of FIG. 1.

FIG. 5 is a rear view of the electronic game machine of FIG. 1.

FIG. 6 is a top view of the electronic game machine of FIG. 1; and,

FIG. 7 is a bottom view of the electronic game machine of FIG. 1.
